WATER HEATER

Gilbert Wilkes, Jacksonwald, and Frank M. Reed,
Clearfield, Pa.

Application August 15, 1935, Serial No. 36,406

8 Claims. (Cl. 122—26)

This invention relates to domestic water heaters and has for an important object thereof the provision of a water heater operated by a heat pump.

5 An important object of the invention is the provision of an arrangement such that a maximum heating efficiency may be derived from the pump.

10 A further object of the invention is the provision of an arrangement such that water supplies of different temperatures may be made available.

15 Another object of the invention is the provision of means whereby, during periods of excessive demand, the heat pump may be supplemented by an electrical heating unit.

These and other objects we attain by the construction shown in the accompanying drawings wherein, for the purpose of illustration, we have shown a preferred embodiment of our invention and wherein:

20 Fig. 1 is a vertical sectional view through a water heater constructed in accordance with our invention;

25 Fig. 2 is a view partially in section and at right angles to the view of Fig. 1;

Fig. 3 is a section on line 3—3 of Fig. 2;

Fig. 4 is a section on line 4—4 of Fig. 2;

Fig. 5 is a diagrammatic view showing the electrical controls and connections; and

30 Fig. 6 is a perspective view showing the water heater casing.

Referring now more particularly to the drawings, the numeral 10 designates a suitable base from which, through standards 11, a tank base 12 is supported. This tank base, in turn, supports the main tank wall 13 and an outer cover 14 spaced from the main tank wall, the space between the main tank wall and the outer cover being filled with suitable insulation not herein disclosed. The tank, adjacent its upper end, has a horizontal partition 15 dividing the interior of the tank into upper and lower chambers 16 and 17. Outlets are provided from the upper portions of compartments 16 and 17 as indicated at 18 and 19 respectively, and an inlet 20 is provided for the lower end of compartment 17.

45 Located in the space between the tank bottom 12 and the base 10 is a motor compressor unit 21 together with an evaporator unit 22. The 50 outlet from the compressor enters the compartment 16, forms a condenser super-heat zone coil 23 in this compartment and is then led downwardly through the partition 15 to a point adjacent the lower end of compartment 17 where the 55 saturated zone coil 24 of the condenser is formed.

From this coil the usual connection is made to the inlet of evaporator 22. Transfer of liquid from compartment 17 to compartment 16 is accomplished through the nozzle 25 which is circumferentially directed in compartment 16. A thermostat 26 controls the operation of the motor compressor unit and is preferably located at a point adjacent the lower end of compartment 17 where it will be rapidly affected by incoming cold water. Compartment 16 is provided with an 10 electrical heating unit 27 controlled by a thermostat 28, which thermostat is preferably arranged in a circuit 29 including a manually controlled switch.

15 Through segregation of the liquid in the upper part of the tank, it is possible to maintain in the compartment 16 a supply of water at relatively high heat, say 135 to 160 degrees, while in the upper end of compartment 17 a temperature of approximately 135 degrees will be attained. The 20 use of the nozzle 25 insures ability to draw off the major portion of the hotter water without comingling with the replenishing liquid received from compartment 17, for the nozzle causes rotative motion of the incoming liquid and of the 25 entire mass within compartment 16 accentuating by centrifugal force the segregation resulting normally from the difference in specific weights of the cooler and hotter liquids, and causes the hotter liquid to rise to the domed top at the 30 center for passage through the centrally disposed outlet 18. As fresh water enters compartment 35 17, the thermostat sets the motor compressor unit in operation and since the coil 23 in compartment 16 forms a super-heat zone and is located well toward the periphery of compartment 16 where it will immediately contact with the incoming water from compartment 17, the incoming water is rapidly and highly heated. The 40 nozzle is so directed that the flow of the liquid is in counter-flow relation to the super-heat coil; that is to say, it passes from the outlet toward the inlet of the super-heat coil so that a maximum efficiency with heat exchange is provided. For 45 emergency use, the switch 30 may be closed so that the electric heater may supplement the action of the heat pump.

In addition to its function as a water heating unit, the heat pump is likewise utilized in room cooling, the base structure being provided with 50 a grille, louvers or the like indicated at *g* and positioned to permit escape of the air drawn through the evaporator unit 22 by the unit fan *f*.

The arrangement illustrated being obviously capable of considerable modification without de- 55

parting from the spirit of our invention, we do not wish to be understood as limiting ourselves thereto except as hereinafter claimed.

We claim:

5. 1. In a water heater, a tank having upper and lower compartments separated by a partition, means to heat the contents of the lower compartment, additional means to heat the contents of the upper compartment to a higher temperature, 10 means to transfer water from the lower to the upper compartment causing the water to rotate in the upper compartment, an inlet for the lower end of the lower compartment, and a centrally disposed outlet in the upper end of the upper compartment.
10. 2. In a water heater, a tank having upper and lower compartments separated by a partition, means to heat the contents of the lower compartment, additional means to heat the contents of the upper compartment to a higher temperature, 15 means to transfer water from the lower to the upper compartment causing the water to rotate in the upper compartment, an inlet for the lower end of the lower compartment, a centrally disposed outlet in the upper end of the upper compartment, and an outlet for the upper end of the lower compartment.
15. 3. In a water heater of the type described, a tank having upper and lower compartments, an inlet at the lower end of the lower compartment, an outlet for the upper end of the upper compartment, means to transfer fluid from the upper end of the lower compartment to the upper compartment and a heat pump including a condenser comprising a coil located in said upper compartment, a coil located in the lower end of the lower compartment and means to circulate a refrigerant to be condensed through said condenser, said coils being arranged in series and 20 the coil of the upper compartment being first to receive the refrigerant to be condensed, said transfer means being constructed and arranged to cause the fluid to travel about said coil in a direction opposite to the flow of refrigerant with- 25 in the coil.

4. The structure of claim 1 wherein the heat-

ing means of the upper compartment comprises a coil paralleling the tank wall and through which a heating medium is circulated and the direction of rotation of transferred water in the upper compartment is counter to the direction of movement of the heating medium in the coil. 5

5. In a fluid heater, a compartment having a coil paralleling the wall thereof, a domed top for the compartment having an outlet substantially axial to the coil, means to circulate a heating 10 medium through said coil and means to introduce fluid to said compartment constructed and arranged to cause the entering fluid to rotate in the compartment in a direction opposite to the direction of flow of heating medium in the coil. 15

6. In a water heater of the type described, a self-contained unit comprising a base, a tank, means to support the tank in spaced relation to the base, a heat pump comprising a motor compressor unit and an evaporator located between 20 the tank and base, and a condenser disposed within the tank, and an air circulating means passing air over said compressor unit and to said evaporator.

7. A device as claimed in claim 6 wherein the 25 tank base is engaged by a jacketing means trapping heated air rising from the motor compressing unit and bringing this air into heat transfer relation to the lower end of the tank.

8. In a water heater of the type described, a 30 single water-storage tank, a partition dividing the tank into a small upper and a large lower compartment, the upper compartment having a domed upper wall provided centrally with an outlet, a heat pump including a condenser coil having superheat and saturate zones, the superheat zone being disposed within and extending circumferentially of the upper compartment and the saturate zone being disposed within the lower compartment, means to transfer fluid from the 35 upper end of the lower to the upper compartment and a thermostatically controlled direct heater disposed in the upper compartment adjacent the outlet thereof.
